UNITED STATES PATENT OFFICE.

ADOLPH M. HOLSTEIN, OF SYRACUSE, NEW YORK.

DESIGN FOR A CREST ORNAMENT FOR FURNITURE, CASKET, INTERIOR, OR EXTERIOR DECORATION.

53,008.

Specification for Design.

Patented Feb. 18, 1919.

Application filed October 15, 1918. Serial No. 258,300. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Crest Ornament for Furniture, Casket, Interior, or Exterior Decoration, of which the following is a specification, reference being had to the accompanying drawing, forming a part hereof.

The drawing is a face view of my ornamental design for crest ornament.

This ornamental design comprises the representation of an arch of the medieval style supported by ornamented scrolls and having a cresting of foliage.

I claim:

The ornamental design for a crest ornament for furniture, casket, interior or exterior decoration, substantially as shown and described.

In testimony whereof, I have hereunto signed my name, at Syracuse, in the county of Onondaga, and State of New York, this 24th day of September, 1918.

ADOLPH M. HOLSTEIN.
